LIGHTNING ARRESTER

Hans Vatter, Berlin-Charlottenburg, Germany,
assignor to Westinghouse Electric & Manufacturing Company, East Pittsburgh, Pa., a corporation of Pennsylvania

Application May 17, 1939, Serial No. 274,156
In Germany May 19, 1938

18 Claims. (Cl. 175—30)

This invention relates to lightning arresters to be employed primarily for protecting relatively low-voltage direct current lines or apparatus, although it may also be employed for protecting alternating current equipment, and has for a particular object the positive interruption of any power-follow current in the lightning arrester after the surge has subsided.

According to my invention, the lightning arrester, briefly, consists of a ceramic housing provided with terminal electrodes connectible, respectively, to a ground circuit and to the equipment which is to be protected. Within the housing is disposed a movable electrode having a ferrous or magnetizable portion. During a discharge of the arrester, the movable electrode is in arcing relation to one or both of the terminal electrodes, and can be moved by a coil about the housing so that the space between the movable electrode and one of the terminal electrodes can be considerably increased to the extent of interrupting the flow of current. The ground circuit is such that when the arrester breaks down upon the occurrence of an over-potential or surge, a voltage drop in the grounding circuit will serve to energize the coil.

In one embodiment of my invention, the arc between the fixed and movable electrode is suddenly and considerably decreased in size in a manner to aid the extinction of the arc. I accomplish this by causing a tip of the movable electrode to enter a cut-out portion or cavity in the form of an opening or bore in an insulating member within the arrester so that the arc, in effect, is cut off.

Other objects and novel features of my invention will be apparent from the following description thereof, which is to be taken in conjunction with the drawing, in which:

Figure 1 is a longitudinal cross-sectional view of one form of lightning arrester embodying the principles of my invention;

Fig. 2 is a schematic diagram of a protective circuit including the lightning arrester; and

Figs. 3 and 4 are longitudinal cross-sectional views of modified forms of an arrester.

Referring more particularly to the embodiment disclosed in Figure 1, the housing consists of an open-ended tube 1 of some ceramic material, preferably wet-process porcelain. In the ultimate arrester, the ends of the tube are sealed by terminal electrodes comprising a metal cap 2 at one end of the tube and a metal cap 3 at the other end. The caps preferably are formed with cylindrical portions at their centers into which are

secured conductors 4 and 5. The end terminals also have protruding cylindrical electrode members 6 and 7 conductively connected to the caps, and formed preferably of some non-arching and arc-extinguishing metal, such as, for example, brass. The complete terminal electrodes are soldered to the tube 1 so as to form a gas-tight enclosure, and this may be accomplished in any suitable manner as, for example, by coating the ends of the porcelain tube 1 with a metal layer which will solder to the caps 2 and 3.

As may be observed in Fig. 1, the electrodes 6 and 7 extend partially into the tube 1 to about ceramic insulating inserts or members 8 and 9 fixed in the tube 1 in axially spaced relation. Each of the members 8 and 9 is provided with an axial bore or opening 10 and 11, respectively, in which slide the stub electrode sections 12 and 13, respectively, of an intermediate connecting electrode indicated in its entirety by the reference numeral 14. A ferro-magnetic cylinder 15 completes the structure of the connecting electrode 14.

In the normal, vertical, operating position of the arrester, the cylinder 15 rests upon the member 9 so that the lower part of the stub electrode 13 is axially disposed somewhat within the cylindrical electrode 7, and a tip of the other stub electrode 12 is similarly disposed within the electrode 6.

A coil 16 is secured externally about tube 1 and disposed in a manner that, when energized, it will attract the magnetizable cylinder 15 so as to raise the connecting electrode 14. The space 17 between the members 8 and 9 is sufficiently large so that the upward movement of the cylinder 15 will carry the stub electrode 13 completely into the bore 11 of the member 9.

Fig. 2 shows schematically a manner in which the lightning arrester of Fig. 1, as well as those of Figs. 3 and 4, to be subsequently described, may be connected in a protective circuit. The line 19 is indicative of a direct-current transmission wire or other apparatus or equipment which is to be protected against overvoltage. It is connected by a conductor 20 to the conductor 4 of the upper terminal apparatus, and thereby is conductively connected to the inner fixed electrode 6. The other terminal of the arrester is connected to a resistor 21 which, in turn, is connected to ground through a conductor 22. The coil 16 is connected across the resistor 21, or a part thereof, so that upon breakdown of the arrester, the current flowing through the resistor

will establish a potential sufficient to energize the coil 16.

The operation of the arrester of Fig. 1 should be obvious to those skilled in the art. Upon the occurrence of an overvoltage, a ground circuit is established including an arc between the electrode 6 and the tip of the stub electrode 12, current continuing across the rest of connecting electrode 14 to the tip of its other stub electrode 13. The circuit is completed by an arc across the breakdown path between the electrode 7 and the tip of stub electrode 13, and a path to ground through the resistor 21. The surge or overvoltage may be of practically instantaneous appearance, but the power follow current will be sufficiently continuous to energize the coil 16, thereby raising the connecting electrode 14. The raising of the connecting electrode 14, of course, pulls the stub electrode 13 thereof into the bore 11, thereby elongating the arc breakdown path between this stub electrode and the electrode 7. When the arc gets sufficiently long so that it cannot be sustained by the normal voltage of the system, it will interrupt, thereby deenergizing the coil 16 and permitting the center electrode to restore to normal position, awaiting a subsequent over-voltage.

In order to aid the extinguishing of the arc between the electrode 7 and the stub electrode 13, the bore 11 of the member 9 is made only slightly larger than the stub electrode 13 so that a cutting off action occurs when the tip of the stub electrode is immersed in the member 9. To aid in the extinction of the arc, the extreme tip of the stub electrode 13 may be provided with an attachment 23 of a semi-conducting or insulating material. A ceramic substance, similar to that of the tube 1, may be employed.

It may be observed that in the movement of the connecting electrode 14, the arc path between the electrode 6 and the stub electrode 12 is not changed to any appreciable extent, since the stub electrode merely rises axially into the cylinder comprising the electrode 6. In addition, the bores or openings 10 and 11 form a guiding means assuring that the connecting electrode 14 is properly positioned during its raising and lowering movements inside the tube 1. If desired, the cylinder 15 may also be formed to slide along the inner surface of the tube 1 and to fit its bore rather snugly, so that it, too, aids in guiding the movement of the connecting electrode.

Fig. 3 shows a further embodiment of my invention in which the lightning arrester, indicated in its entirety by the reference character 30, has only a single discharge space located in its lower portion. The lower cap 3' and the cylindrical electrode 1' are similar to the elements 3 and 7 of the lightning arrester of Fig. 1, being integral and secured to the housing in a gas-tight manner for a purpose to be later apparent. The upper part of the lightning arrester 30 has a cap 31 in the center of which is soldered or welded, or otherwise secured, the conductor 32.

The connecting electrode in the embodiment of Fig. 3 comprises a lower stub electrode 33 integral with a magnetizable metallic cylinder 34. The stub electrode 33 and the cylinder 34 compose the central connecting electrode 35 which is normally maintained in a lowermost position by means of a spring 36. In order to position the spring, the conductor 32 and the cylinder 34 may have small protuberances 37 encircled by the extremities of the spring. A pigtail 38 shunts

the spring 36 so that the latter need not be called upon to conduct electricity.

It may be observed in Fig. 3 that the housing of the arrester is formed integral with a member 39 having a central bore or opening 40 in which the stub electrode 33 slides.

The operation of the arrester of Fig. 3 is very similar to that of Fig. 1, except that a single arc gap only is provided at the lower terminal. Upon energization of the coil 16' during a discharge of the lightning arrester, the connecting electrode 35 is raised against the action of the spring 36 and the arc is extinguished between the electrode 1' and the stub electrode 33 as was described for the like operation of the arrester of Fig. 1. However, an extra space 41 between the top extremity of the electrode 1' and the bottom of the member 39, can be made as short or as long as found necessary so that the arc is first elongated before it is cut off upon complete immersion of the stub electrode 33 in the bore 40.

In the lightning arrester of Fig. 4, indicated in its entirety by the numeral 50, the members of ceramic material shown in the prior figures for abruptly diminishing the arc thickness, have been eliminated, the arc extinction depending on the elongation of the space between a lower electrode 51 and a lower stub electrode 52 of a center connecting electrode 53. In this arrester, an outside tube 54 of some suitable ceramic material, is provided with terminal electrodes including caps 55 and 56 and internal cylindrical electrodes 51 and 57, conductively connected to the respective caps. In this embodiment, the connecting electrode 53 is formed with a somewhat elongated central body portion 58 of ferrous material which is provided with ball bearings 59 and 60 at each end so that this body portion acts as a guide for positioning the entire electrode 53 during its movement within the tube 54.

The body portions 58 is centrally bored and threaded from each end so that the lower stub electrode 52 may be secured therein and also an upper stub electrode 61. The lower fixed cylindrical electrode 51 and the stub electrode 52 are deliberately made relatively short compared to the fixed cylindrical electrodes 57 and stub electrode 61 in the upper part of the arrester. In order to insulate the central electrode 53 from the electrodes 51 and 57 in the extreme positions of movement of the center electrode, the body portion 58 is provided with insulating contact spacers or members 62 and 63 which are annular in shape and extend around the contiguous parts of the stub electrodes 52 and 61. The axial length of the portions of these spacers 62 and 63 which contact the cylindrical electrodes 51 and 57 is greater than the minimum distance between the stub electrodes and the cylindrical electrodes so that the arcs formed upon a discharge will flow to the stub electrodes rather than directly from one of the electrodes, say 51, to the body portion 58. This construction is preferred so that the stub electrodes can be made, as in the other embodiments, of an arc-extinguishing metal.

Much better results can be had if the arresters of the different embodiments are filled with a gas at a sub-atmospheric pressure, and I have found that if the tube is filled with hydrogen at a pressure of 60 mm., an arc length of 45 mm. is enough to cause an arc voltage drop of 800 volts. Thus, the elongation of the arc alone can be relied upon to clear the protective

circuit of Fig. 2. In order to exhaust the lightning arrester, one of the terminal conductors may be formed hollow, as shown in Fig. 4, and the corresponding cap also formed with a small aperture. After the arrester has been exhausted and filled with the desired gas at a suitable pressure, the conductor 10 may be pinched and welded into a unit mass, sealing the arrester tube. Some times soldering can be employed, in which case the hollow terminal conductor is tinned on the inside and then pinched and heat sealed. The method by which the arrester is assembled and filled with a gas is not part of this invention since many suitable processes or methods may be employed.

In the protective circuit, the resistor 21 of the protective circuit shown in Fig. 2 may be made of any suitable substance, but I have found it preferable to employ a block which limits the discharge current and also prevents the voltage across it from rising to too great a proportion of the voltage between the protected equipment 19 and ground, which would destroy the efficacy of the lightning arrester. Blocks of the character referred to are now well known to the art and usually comprise a mixture of silicon carbide, clay and lamp black, as more particularly disclosed in U. S. Patent No. 2,000,719 granted May 7, 1935, to J. Slepian et al.

While I have described my invention in different embodiments, many other equivalents are obvious to those skilled in the art and the teachings of my invention can be applied to arresters of equivalent designs.

I claim as my invention:

1. An over-voltage protective device comprising a hollow insulating tube, an electricity-conducting means secured gas-tight to one end of said tube, said means comprising a cylindrical electrode inside said tube near said end thereof, an electricity-conducting means secured gas-tight to the other end of said tube, said tube being filled with a gas at sub-atmospheric pressure, means within said tube for forming a discharge path between the first and second said means, the last said means comprising a movable electrode axially disposed with respect to said cylindrical electrode, and spaced from its sides, means for moving said movable electrode out of said cylindrical electrode, and means for guiding said movable electrode during such movement.

2. An over-voltage protective device comprising a hollow, ceramic tube, an electricity-conducting means secured gas-tight to one end of said tube, said means comprising a cylindrical electrode inside said tube near one end thereof, an electricity-conducting means secured gas-tight to the other end of said tube, the last said means comprising a cylindrical electrode inside said tube near said other end, said tube being filled with gas at sub-atmospheric pressure, said electrodes being spaced from each other and substantially axially aligned, a movable connecting electrode within said tube disposed between said cylindrical electrodes and having tips in arcing relation to said electrodes, and means for moving said connecting electrode to increase the spacing between one of said cylindrical electrodes and its corresponding tip.

3. An over-voltage protective device comprising a hollow ceramic tube, an insulating member within said tube intermediate its ends, an electricity-conducting means secured to said tube and comprising a fixed electrode within said tube at one side of said member, a movable electrode

having a magnetizable section and an electrode section normally in arcing relation to the said fixed electrode, said member being provided with an opening into which said electrode section may move, said opening closely fitting said electrode section, and means for moving said movable electrode upon breakdown of said device whereby said electrode section is moved into said opening.

4. An over-voltage protective device comprising a hollow ceramic tube, an insulating member within said tube intermediate its ends, an electricity-conducting means secured to said tube and comprising a fixed electrode within said tube at one side of said member, a movable electrode 10 having a magnetizable section and an electrode section normally in arcing relation to the said fixed electrode, said member being provided with an opening into which said electrode section may move, said opening closely fitting said electrode section, means for moving said movable electrode upon breakdown of said device whereby said electrode section is moved into said opening, 15 said fixed electrode and said electrode section being so dimensioned that upon movement of the movable electrode the space between its electrode section and the said fixed electrode is increased before the said electrode section moves into said opening.

5. The structure of claim 3 wherein said electrode section has a tip of a substance whose electrical conductivity, compared to the remainder of said electrode section, is relatively considerably less.

6. The structure of claim 4 wherein said electrode section has a tip of a substance whose electrical conductivity, compared to the remainder of the electrode section, is relatively considerably less.

7. The structure of claim 3 characterized by 30 said tube being gas-tight and filled with gas at a sub-atmospheric pressure.

8. The structure of claim 4 characterized by 35 said tube being gas-tight and filled with gas at a sub-atmospheric pressure.

9. The structure of claim 3 wherein said electrode section has a tip of a substance whose electrical conductivity, compared to the remainder of said electrode section, is considerably less, relatively, and said tube is gas-tight and filled with gas at a sub-atmospheric pressure.

10. An over-voltage protective device comprising a hollow insulating tube, an electricity-conducting means secured to one end of said tube, said means comprising a fixed electrode inside said tube near said end thereof, a second electricity-conducting means secured to the other end of said tube, the said second means comprising a fixed electrode inside said tube near said other end thereof, said electrodes being aligned and spaced from each other with an intermediate section of said tube between said electrodes, a movable connecting electrode within said tube, guiding means in said intermediate section, said connecting electrode being provided with tips 40 extending away from each end of said guiding means and in arcing relation with said fixed electrodes.

11. The structure of claim 10 wherein one of 45 said fixed electrodes and one of the co-operating tips of said connecting electrode are concentric but spaced, and of relatively extended length, and the other of said fixed electrodes and the other co-operating tip of said connecting electrode are concentric but spaced, and of relatively short 50 length, and means for moving said connecting

electrode whereby the arcing relation between the first said one fixed electrode and one tip is not substantially changed while that between the said second fixed electrode and second tip is considerably changed.

12. An over-voltage protective device comprising a hollow insulating tube, an electricity-conducting means secured to one end of said tube, said means comprising a fixed electrode inside said tube, a second electricity-conducting means secured to the other end of said tube, the said second means comprising a fixed electrode inside said tube at said other end thereof, said fixed electrodes being aligned and spaced from each other with an intermediate section of said tube between said electrodes, a movable connecting electrode within said tube, guiding means in said intermediate section, said connecting electrode being provided with tips extending away from each end of said guiding means and in arcing relation with said fixed electrodes, said guiding means being a ferrous cylindrical member fitting the hollow of said tube, and having bearing means at each end for sliding in the hollow of said intermediate section.

13. An over-voltage protective device comprising a hollow insulating tube provided with electricity-conducting means secured gas-tight at each end, said means at each end including a hollow cylindrical electrode fitting the inside of said tube, said electrodes being spaced, a movable connecting electrode within said tube comprising a guiding portion, sliding inside said tube intermediate the ends of said electrodes, insulating spacers to insulate said guiding portion from said cylindrical electrodes, electrode stubs at each end of said guiding portion and concentric with said cylindrical electrodes but spaced therefrom, said connecting electrode in normal position having one stub substantially completely inserted in one cylindrical electrode and the other stub almost withdrawn from the second cylindrical electrode, and means to move said connecting electrode, whereby the one stub is withdrawn from said one cylindrical electrode to increase the spacing between the two while the other is inserted in said second electrode.

14. The structure of claim 13 in which said spacers are fixed adjacent said electrodes and the said one stub is provided with an insulating tip.

15. The structure of claim 13 in which said spacers are annular and fixed to the ends of said guiding portion, and said stubs are conductively secured to said guiding portion.

16. An electrical protective device comprising a container filled with a gas under sub-atmospheric pressure, a pair of separable electrodes in said container, an insulating member having an opening into which one of said electrodes may be drawn, means to separate said electrodes, said electrodes and member being so arranged that when the electrodes are first separated the common discharge path between them is large and after separation the common discharge path is confined within said opening.

17. In an electrical protective system, a protective device including a pair of separable electrodes, means for separating said electrodes to interrupt any arc between them, a protective circuit including a resistance to ground from said device, said electrodes being in series with said resistance, said resistance being of the type that can pass necessary amounts of current without appreciable increase of voltage drop across it, said separating means being energized by a voltage drop across said resistance.

18. An over-voltage protective device comprising a hollow insulating tube, a fixed electrode in said tube, electrode means comprising a movable electrode in said tube, having an end normally in spaced arcing relation to said fixed electrode, an insulating member in said tube having an opening into which said end of said movable electrode can move, means for moving said movable electrode so that said end of said movable electrode moves away from said fixed electrode and into said opening for abruptly narrowing the arc path between the said end of said movable electrode and said fixed electrode to encourage extinction of the arc, said electrode means restoring said end of said movable electrode to its normal spaced arcing relation with respect to said fixed electrode upon extinction of the arc.

HANS VATTER.
